UNITED STATES PATENT OFFICE

LEO W. KENNEDY, OF DETROIT, MICHIGAN

DIVIDER SUPPORT

Application filed October 2, 1929. Serial No. 396,851.

This invention relates to show cases and more particularly to an improved construction of partition support therefor.

In show cases as now commercially produced and particularly with that type of show case employed for displaying candy and the like, it is customary to provide a partition extending upwardly from the floor of the show case to divide the interior of the show case into apartments whereby different types, grades or kinds of merchandise may be properly displayed. Frequently these partitions are formed of glass and moreover the height of these partitions frequently varies as does also the thickness thereof. Where partitions of any appreciable height are employed and particularly where any considerable amount of lateral pressure is exerted thereon, it becomes necessary to adequately grip and support the partitions to hold the same firmly in position and prevent the same from breaking.

In accordance with the present invention I provide an adjustable partition support provided with a slotted or jaw-like portion designed to embrace and grip the partition to thus fully and adequately support the same.

It is an important object of this invention to provide an adjustable partition support of this character and one which may be quickly and economically manufactured; which is rigid in construction and may be quickly and easily installed and adjusted.

The several objects of this invention, together with the novel details of construction thereof will be made more apparent as this description proceeds, especially when considered in connection with the accompanying drawings, wherein

Figure 1 is a fragmentary perspective view of a show case having a partition supported therein by means of my improved partition support;

Figure 2 is a separated perspective view of one of the supporting members;

Figure 3 is a side elevational view of one of the supporting members; and

Figure 4 is a horizontal sectional view

taken substantially on the plane indicated by line 4-4 in Figure 3.

Referring now more particularly to the drawings, wherein like reference characters indicate like parts, and especially to Figure 1 thereof, it will be noted that there is illustrated, fragmentarily, a show case 10 having a bottom or floor 11, the interior of the show case being divided by means of a partition 12 secured in place by partition supports indicated generally by the reference character 13.

By reference to Figure 2 it will be noted that each partition support consists of a pair of members 14 and 15 each of which comprises an upwardly extending portion 16 which terminates at its lower end in a shoulder 17 and a laterally extending portion 18. The laterally extending portions 18 are adapted, in the assembled position of the support, to lie side by side with the free end of each extension 18 underlying the shoulder 17 of the other member. When assembled in this manner the upstanding portions 16 together provide a partition receiving slot 19. One of the lateral extensions 18 is provided with a threaded aperture 20, while the other member is provided with a slot 21. A screw 22 extends through the slot 21 and into the threaded aperture 20 to thus adjustably secure the two members 14 and 15 together. One of the members is provided with an enlargement formed with an aperture 23 through which a screw 24 may be passed downwardly into the floor 11 of the show case for securing the support thereto. Obviously the two support sections 14 and 15 may be relatively adjusted, even when the support is secured to the floor of the show case by movement of the section 14. Therefore the support may be adjusted to accommodate partitions of different thickness.

It will be noted that the upstanding portions 16, which provide the partition receiving slot, may be made of any desired length, thus providing adequate support for partitions of considerable height. Moreover, by adjusting the support sections so as to grip the partition, relative movement of the par-

tion which might result in breakage thereof is eliminated. Any pressure tending to separate the upper ends of the upstanding portions 16 is resisted by reason of the fact that the lateral extension 18 of each member underlies the shoulder 17 of the other member. If desired, the adjacent faces of the upstanding portion 16 may be lined with felt or other cushioning material (not shown).

10 Reservation is made to make such changes in the details of construction as may come within the purview of the accompanying claims.

I claim as my invention:

15 1. In a show case, a partition and a support therefor comprising a pair of members each having an upstanding portion terminating at its lower end in a shoulder and a lateral extension, the lateral extension of one member underlying the shoulder of the other member, the upstanding portions together comprising a slot for receiving said partition and mean for adjustably securing said members together.

20 2. In a show case, a partition and a support therefor comprising a pair of members, each member having a lateral extension and an adjacent horizontal shoulder, each member also having an upstanding portion, the upstanding portions of said members together forming a partition receiving slot, the lateral extension of each member underlying the horizontal shoulder of the other member and means for adjustably securing said members together.

25 3. In a show case, a partition and a support therefor comprising a pair of members, each member having a lateral extension and an adjacent horizontal shoulder, each member also having an upstanding portion, the upstanding portions of said members together forming a partition receiving slot, the lateral extension of each member underlying the horizontal shoulder of the other member and means for securing said support to the floor of the show case and means for adjustably securing said members together.

40 4. In a show case, a partition and a support therefor comprising a pair of members, each member having a lateral extension and an adjacent horizontal shoulder, each member also having an upstanding portion, the upstanding portions of said members together forming a partition receiving slot, the lateral extension of each member underlying the horizontal shoulder of the other member, a slot in one of said members, and a threaded member extending through said slot and into a threaded opening in the other of said members for adjustably securing said members together.

45 5. In a show case, a partition and a support therefor comprising a pair of members, each member having a lateral extension and an adjacent horizontal shoulder, each

member also having an upstanding portion, the upstanding portions of said members together forming a partition receiving slot, the lateral extension of each member underlying the horizontal shoulder of the other member and means for securing one of said members to the floor of the show case and means for adjustably securing said members together.

70 In testimony whereof I affix my signature.
